United States Patent Office.

HENRY J. ROGERS, OF BALTIMORE, MARYLAND.

Design No. 2,599, dated March 19, 1867.

DESIGN FOR A SET OF SIGNAL FLAGS.

The Schedule referred to in these Letters Patent and making part of the same.

TO ALL WHOM IT MAY CONCERN:

Be it known that I, HENRY J. ROGERS, of the city of Baltimore, in the county of Baltimore, and State of Maryland, have originated and designed a new Pattern for Telegraphic Signal Flags, of which the following is a full, clear, and exact description, reference being had to the accompanying specimens or drawings, making part of this specification.

The size, color, and material of the flags may be varied to suit the taste or judgment of the makers.

Claim.

What I claim as my invention, and desire to secure by Letters Patent, is—

The designs or patterns for telegraphic signal flags, substantially as herein set forth and shown.

HENRY J. ROGERS.
